UNITED STATES PATENT OFFICE.

ROBERT R. GOSHORN, OF JASONVILLE, INDIANA, ASSIGNEE, BY DIRECT AND MESMEE ASSIGNMENTS, TO THE ALL-WAYS-HOT MFG. CO., OF JASONVILLE, INDIANA.

MAGNETIC LIQUID HEATER.

Application filed August 16, 1927. Serial No. 212,855.

This invention relates to water heaters, preferably for domestic use, and has for its object to provide such a device which may be operated by the ordinary house current, and which is comprised of few parts which are readily assembled into a unitary structure of comparatively low cost.

A further object of the invention resides in the provision of a water heater in which all of the piping is within the tank thereby reducing the problem of insulation to a minimum and bringing the efficiency of the heater to a maximum.

Another object of the invention consists in providing an electrically operated water heater in which the water or other liquid is gradually heated in the pipes until it reaches its maximum at the point of discharge into the top of the tank thus avoiding undue heating of the primary coils of the heater.

A further object of the invention resides in combining with a heater a thermostat which is so positioned within the tank as to be most responsive to changes of temperature in the tank so as to maintain the water at the desired temperature.

Another object of the invention consists in the provision of a coil and a condenser connected in series and serving to maintain the heating effects by compensating for phase displacement caused by inductive effects in the transformer which supplies the current.

Other objects and advantages of the invention will be apparent from the following description taken in connection with the accompanying drawing; in which

Figure 1 is a vertical section through the complete heater.

Figure 2 is a horizontal section taken on line 2—2 of Figure 1; and

Figure 3 is a horizontal section taken on line 3—3 of Figure 1.

Referring to the drawing in greater detail the numeral 1 indicates generally the apparatus which includes upper and lower tanks 2 and 3, united by a metal band 4, and a conventional base or pedestal 5. The tank 2 serves as a receptacle for the water or other fluid being heated, while the lower tank or compartment 3 holds the heating unit designated generally by the numeral 6.

Secured to the base 7 of the compartment 3 as by means of clips or other fastening

means 8, is a closed laminated iron core 9 around which are wound the primary coils 10. The secondary winding of the transformer is formed of the pipe coils 11 which have their terminals 12 and 13 provided with conventional pipe unions 14 and 15. It will be noted that the primary coils 10 contain a great many turns of comparatively small high resistance wire, while the secondary coils 11 are each composed of a few turns of heavy low resistance tubing. This gives a high transformation ratio so that when alternating current at approximately 110 volts is supplied to the primary coils, a very heavy current will flow in the low resistance secondary and will generate heat and raise the temperature within the tubing.

Numeral 16 indicates a pipe connection from the water supply and connected to the upper end of the tank 2 and coupled with this pipe is a pipe 17 which extends downwardly to a point adjacent the bottom of the tank, thereby discharging the relatively cold water into the tank at a point close to its bottom. The discharge pipe for the heated water is indicated by numeral 18 and, as will be noted, is connected to the upper end of the tank so as to carry off the hot water as desired.

The bottom of the tank 2 is provided with an opening surrounded by a threaded boss 19 and in which is threaded a metal sleeve 20 extending from the bottom of the tank 2 to a point adjacent its top. Positioned within the pipe or sleeve 20 and spaced therefrom is an extension tube 21 which is connected with the coil terminal 13 by means of the pipe union 15. This tube 21, as stated, is spaced from the inner wall of the sleeve 20 and is thus entirely out of contact with any portion of the tank. To provide for the secondary circuit, however, the upper end of the tube 21 is welded or otherwise intimately connected with the upper end of the sleeve 20.

A short pipe or tube 22 is threaded into the bottom of the tank 2 by means of a boss 23 and is connected with the second terminal of the pipe coils 11 by means of the union 14.

It will thus be observed that a closed circuit is provided for the secondary winding; the current induced in the coils 11 flowing from terminal 13 upwardly through the tube 21, downwardly through sleeve 20 to the bottom of tank 2, and thence to tube 22 and coil terminal 12. In this connection it

should be noted that the direction of the current is reversed in the tube 21 and sleeve 20 thereby becoming entirely non-inductive. However, due to their very close spacing they produce a decided condenser effect which serves to increase the power factor of the heater. For instance, the tube 21 will serve as one plate of the condenser, sleeve 20 as another, and the air gap as the third plate 10 of the condenser. There is thus presented a condenser operating at a very low voltage having quite a large capacity, in fact a capacity which to a great extent counteracts the inductance loss occasioned by magnetic 15 leakage around the transformer and secondary coil.

The transformer core 9 possesses considerable electrical inductance and this will tend to produce phase displacement between 20 the current and electromotive force and hence to decrease the effective heating value of the secondary current. In order to compensate for this effect I place a winding 44 on the core 9 and connect a condenser 45 25 in series with it. The condenser 45 is of such a size as to produce a small flux component of leading power factor in the core 9 just sufficient to balance the lagging effect of the inductance of the core. In this manner 30 the reactive component in the secondary current is kept at a minimum and the maximum heating effect is obtained from the transformer.

From the above description of the secondary circuit it will be apparent that the cool water entering the tube 22 is gradually heated as it passes through the coils 11, the temperature thereof increasing as the water passes upwardly through the tube 21 due to 40 the fact that it has been longest exposed to the heat within the tubing. The annular air space between the tube 21 and sleeve 20 also serves as an insulation for these parts. Furthermore, the fact that the maximum 45 temperature of the water is not reached until the water reaches a point adjacent the top of tank 2, prevents serious defects and loss of efficiency in the heating unit due to the fact that the primary windings are not uniformly heated and also the fact that the use of heat insulating material about these parts is rendered unnecessary.

To automatically control the temperature to which the water in the tank 2 is raised I 55 have provided a thermostat which comprises a tube 24 provided with an enlarged pocket 25 at its lower end and a substantially semi-spherical compartment 26 at its upper end provided with a flexible diaphragm, preferably of metal. This thermostat is threaded 60 into opening 27 in the upper end of tank 2 and forms a leak-proof fit therein. The pocket 25 is preferably filled with ether or other volatile fluid and as the temperature 65 raises the pressure of the gases given off will

bulge the diaphragm 26 upwardly thereby swinging about their pivots the levers 28 and 29 so as to operate the switch 30 to open the primary circuit. Cooperating with the diaphragm 26 is a coil spring 31 and an adjusting screw 32 whereby external pressure on the diaphragm may be varied so as to adjust the thermostat to varying temperatures. 70

It should be particularly noted that the end 25 of the thermostat is located within 75 the tank at a point intermediate the upper and lower ends thereof. The purpose of so locating the thermostat is in order that it may be influenced by the mean temperature of the water within the tank rather than by 80 the hot water at the top of the tank or the relatively cold water at the bottom of the tank, thus tending to maintain the water in the tank at a more nearly even temperature.

The pipe coils 11 are provided with a 85 drain connection 40 to which is attached a faucet 41 and to accommodate these elements the lower end of the side wall of the tank 3 is provided with a slot 42 and a metal flap or the like 43 is secured on the inner face of the tank 2 so as to close the lower portion of this slot. In this connection it should be noted that the pipe 40 inclines downwardly from the pipe coils 11 and is joined thereto in a manner to avoid sharp bends in the 90 pipes. This is of particular importance in that the connection 40 serves as a sediment trap or collector as well as a drain. Organic matter in the water passing through the coils will gradually be deposited and will 95 find its way into the downwardly inclined trap 40, from whence it may be removed by running a wire or other cleaner into the pipe from the exterior of the apparatus or by flushing. It is also desirable to employ a 100 low melting fuse in the primary circuit and I have indicated by numeral 47 such a fuse of conventional type.

In assembling the device the heating unit 105 6 is first secured to the base plate 7 of the tank 3 and the latter is then slipped over the heating unit and its lower edges riveted or otherwise secured to the upturned flange of the bottom 7. The tank 2 is then seated on the upper edge of the tank 3 and secured 110 thereto by means of the band 4. As will appear from an inspection of Figure 3, a door 46 is provided in the side of tank 3 and access may be had through this door for operating the unions 14 and 15 to secure the 115 pipe terminals 12 and 13 to the tubes 22 and 21 respectively.

In the operation of the device, water in the main pipe lines of the city is conveyed 120 to the bottom of the tank through pipe 17 automatically as heated water is withdrawn from the tank by means of pipe 18. As this cool water leads into the tank and lowers the temperature adjacent the pocket 25 of the thermostat the vapors within the tube 125 130

24 are cooled and the diaphragm 26 collapses so as to operate the switch 30 to close the circuit through the primary coils 10, thus supplying secondary current to the pipe 5 coils and tube 21 as above described. This secondary current, of course, will gradually heat the water as it descends through the pipe terminal 12 and around the coils 11 and up through the terminal 13. The water 10 passing upwardly through the terminal 13 will have a temperature of about 100° to 120° F., and the maximum temperature of 170° F. or other temperature to which the thermostat is adjusted will not be attained until 15 the water reaches the upper end of the tube 21.

It will thus be seen that the hottest water is at the upper end of the tank while the relatively cool water is at the lower end of the 20 tank. This gradual heating of the water as it passes upwardly through the tube 21 gives rise to convection currents within the tank 2 and thus tends to cause the water therein to intermingle so as to produce an 25 even temperature. Furthermore, the fact that the maximum temperature is created within the tube 21 has not only the advantages of avoiding undue heating of the primary coils and avoiding the use of heat insulating material about these parts, but also limits the deposit of lime to the tube 21 rather than to the coils 11. This is of paramount importance in that the tube 21 may be readily scaled or cleaned by merely disconnecting the union 15 whereas cleaning 30 of the pipe coils 11, if not entirely impossible, would at least require that the entire apparatus be dismounted and overhauled.

From the foregoing description taken in 40 connection with the accompanying drawings it will be observed that I have devised a comparatively simple and inexpensive type of electric heater of unitary construction, that the device is entirely inclosed within the 45 tank structure, that is, with the exception of the intake and outlet pipes; that the use of heat insulating material is practically eliminated; that the deposit of lime is limited to such parts as may be readily cleaned; and 50 that the thermostatic control is so located as to maintain a maximum quantity of the water in the tank at the temperature at which the thermostat is adjusted.

In accordance with the patent statutes I 55 have described what I now believe to be the best embodiment of the invention, but I do not wish to be understood thereby as limiting myself or the scope of the invention, as many changes and modifications may be 60 made without departing from the spirit of the invention; all such I aim to include within the scope of the appended claims.

What I claim as new and desire to secure by Letters Patent is:

65 1. In a water heater, a transformer includ-

ing a water pipe coil as the secondary winding, a water tank, a conduit leading from said coil through the tank to a point adjacent the top of the tank, said conduit being out of contact with said tank, and means 70 electrically connecting the upper end of said conduit with the tank wall.

2. In a water heater, a transformer including a water pipe coil as the secondary winding, a water tank, said coil having one end 75 electrically connected with the tank, a conduit connected to the other end of said coil and leading through the tank to a point adjacent the top of the tank, said conduit being out of contact with said tank, and means 80 electrically connecting the upper end of the conduit with the tank.

3. In a water heater, a transformer including a water pipe coil as the secondary winding, a water tank, a conduit leading from 85 said coil through the bottom of the tank to a point adjacent the top thereof, said conduit being out of contact with the bottom of said tank, and a metal sleeve connected to the upper end of said conduit and to the 90 bottom of the tank.

4. In a water heater, a transformer including a water pipe coil as the secondary winding, a water tank, said pipe coil having one end electrically connected with said 95 tank, a conduit connected with the other end of said coil and extending to a point adjacent the top of the tank, the bottom of the tank provided with an aperture of greater diameter than the diameter of the 100 conduit and through which the latter extends, and a metal sleeve encircling said conduit but spaced therefrom, the upper and lower ends of said sleeve being connected to the conduit and the bottom of said 105 tank respectively.

5. In a water heater a transformer including a water pipe coil as the secondary winding, a water tank, a conduit leading from said coil through the tank to a point 110 adjacent the top of the tank, said conduit being out of contact with said tank, means electrically connecting the upper end of said conduit with the tank wall, and a second conduit for conducting cold water to a point 115 adjacent the bottom of the tank.

6. In an electric water heater, the combination with a metallic tank structure having a water inlet and a water outlet, of a transformer having a secondary winding 120 composed of pipe coils communicating with the interior of said tank at the top and bottom thereof, and electrically connected therewith, and means electrically associated with the transformer for compensating for 125 phase displacement within the transformer.

7. In an electric water heater, the combination with a metallic tank having a water inlet and a water outlet, of an electrical transformer comprising a magnetic core 130

carrying primary and secondary windings, said secondary winding being made up of pipe coils communicating with the interior of said tank, and means on said core for compensating for the inductance effect of said core.

8. In an electric water heater, the combination with a metallic tank having a water inlet and a water outlet, of an electrical 10 transformer comprising a magnetic core carrying primary and secondary windings, said secondary winding being made up of pipe coils communicating with the interior of said tank, a third winding on said core 15 and a condenser connected in circuit with said third winding for counteracting the effects of phase displacement produced by the inductance of said core.

9. In an electric water heater, the combination with a metallic tank having a water inlet and a water outlet, of an electrical 20 transformer comprising a magnetic core carrying primary and secondary windings, the said secondary windings being made up 25 of pipe coils communicating with the interior of said tank, a fuse of low melting point alloy placed at a point near said pipe coil immediately beneath said tank bottom and being connected in series with the primary 30 coils for the purpose of preventing overheating.

10. A water heater including an upper compartment providing a water tank, and a lower compartment in which an electrical 35 heating unit is mounted, said unit comprising a transformer including a water pipe

coil as the secondary winding, the ends of said coil terminating within the lower compartment, pipe unions carried by the ends of said coil, and pipes supported in the upper 40 compartment and connected to the coil by said unions.

11. A water heater including an upper compartment providing a water tank, and a lower compartment in which an electrical 45 heating unit is mounted, said unit comprising a transformer including a water pipe coil as the secondary winding, and a drain pipe free from sharp bends communicating with said coil and extending downwardly 50 therefrom.

12. In a water heater, a transformer including a water pipe coil as the secondary winding, a water tank positioned above said coil, the ends of said coil being connected to the bottom of the tank and in electrical contact therewith, and a combined drain pipe and sediment collector inclined downwardly from the base of said coil. 55

13. In a water heater, a transformer including a water pipe coil as the secondary winding, a water tank, a conduit leading from said coil through the tank to a point adjacent the top of the tank, a metal sleeve encircling said conduit and spaced slightly 60 therefrom, said sleeve connected at its upper end to said tube and at its lower end to the bottom of said tank, whereby a condenser effect is provided between the sleeve and tube. 65

ROBERT R. GOSHORN.
